SPEED RESPONSIVE SWITCH

Charles H. Bill, South Bend, Ind., and Charles W. Musser, Niles, Mich., assignors to Koontz-Wagner Electric Co., Inc., South Bend, Ind., a corporation of Indiana

Application October 29, 1956, Serial No. 618,722

2 Claims. (Cl. 200—80)

The present invention relates to switches and more particularly speed responsive electrical switches.

One of the principal objects of the present invention is to provide a highly reliable speed responsive electric switch which will withstand vibration and jarring without variation in its operation or responsiveness to the speed of the rotating means being sensed.

Another object of the invention is to provide a speed responsive switch mechanism which can be accurately set to close or open an electrical circuit and which can be readily adjusted in service to any desired speed within a wide range of settings.

Another object of the invention is to provide a sensitive speed responsive electrical switch which is not affected in its operation or performance by extraneous magnetic fields or by temperature and moisture changes.

Still another object of the invention is to provide a sturdy relatively simple speed responsive mechanism which can be readily adapted to a wide variety of applications and which can easily be serviced and maintained in good working condition in the field.

A further object is to provide a speed responsive mechanism which can be used with a number of different types of well known or conventional electrical switches to open or close a circuit when a predetermined speed is reached.

Additional objects and advantages will become apparent from the following description with reference to the accompanying drawings, wherein:

Figure 1 is a longitudinal cross sectional view of our speed responsive switch mechanism, showing certain operative parts thereof in elevation;

Figure 2 is an end view of the switch mechanism with the cover removed to show the switch and switch actuating means;

Figure 3 is a cross sectional view of the fluid drive, showing the rotor and impeller in operative position;

Figure 4 is an end elevational view of the impeller of the fluid drive;

Figure 5 is a side elevational view of the impeller;

Figure 6 is a longitudinal cross sectional view of the impeller;

Figure 7 is an end elevational view of the rotor of the fluid drive;

Figure 8 is a side elevational view of the rotor;

Figure 9 is a longitudinal cross sectional view of the rotor;

Figures 10 and 11 are enlarged views of the switch actuating mechanism showing it in the switch open and switch closed positions, respectively;

Figure 12 is an end view of the switch actuating cam;

Figure 13 is an elevational view of the switch actuating cam and a portion of the drive shaft therefor; and

Figure 14 is a cross sectional view of a microswitch.

Referring more specifically to the drawings and to Figure 1 in particular, numeral 20 designates the housing for the switch mechanism, 22 a removable cover, 24 a fluid drive assembly, and 26 a conventional microswitch

2

connected to terminals 28 and 30 by lead wires 32 and 34, respectively. The base of housing 20 is provided with a flange 36 having a plurality of holes for receiving bolts or studs for mounting the switch mechanism on an engine or the like.

The fluid drive assembly 24 consists of a rotor 40 driven by a shaft 42 journalled in ball bearings 44 and 46 in the base of housing 20, and an impeller 50 for driving a shaft 52 journalled in ball bearings 54 and 56 mounted in a bearing block 58. As seen in Figures 7, 8, and 9 the rotor has a disc-shaped end plate 60 provided with four blades 62 and containing four fluid inlet ports 64 adjacent the inner ends of the blades. A hub 66 formed integrally with plate 60 is secured to shaft 42 and forms a shoulder for engaging bearing 44, which together with a shoulder 68 formed on shaft 42 for engaging bearing 46 prevents end-play of said shaft and rotor. Bearings 44 and 46 are seated in a recess in the base of the housing and are held in spaced relation by spacers 70 and 72, all of said elements being held in said recess by a retainer ring 74 secured to the base by a plurality of screws 76. Shaft 42, which is sealed in a fluid tight relationship with the housing base by two sealing gaskets 80 and 82 disposed in a recess in the end of the base, extends beyond the end of the base and is provided with a square end portion 84 for connecting the shaft to the rotating means to which the switch is responsive.

As seen in Figures 4, 5 and 6, the impeller 50 consists of an end plate 90 and a rim 92 forming a cup-shaped member containing a plurality of equally spaced vanes 96 so arranged that when the rotor and impeller are assembled into operating position blades 62 will rotate freely in the confines of the vanes but in close proximity therewith. A plurality of fluid inlet holes 98 are provided adjacent the center of plate 90 and a plurality of fluid outlet holes 100 are provided in rim 92, one hole 100 being provided adjacent the outer edge of each vane 96. A hub 102 formed integrally with plate 90 is secured to shaft 52 and forms a shoulder for engaging bearing 56, which together with a shoulder 104 formed on shaft 52 for engaging bearing 54 prevents end-play of said shaft and impeller. Bearings 54 and 56 are seated in a recess in bearing block 58 and held in spaced relation by spacers 106 and 108, all of said elements being held in said recess by a retainer ring 110 secured to the block by a plurality of screws 112. Shaft 52 is sealed in a fluid tight relationship with the block by a sealing gasket 114 disposed in a recess in the end of said block.

A fluid chamber 120 is formed in the housing and is closed at the left hand end, as viewed in Figure 1, by bearing block 58 which is sealed in fluid tight relationship with the inside walls of the housing by an O-ring 122 in annular groove 124. The block is held in a fixed position in the housing by a screw 126 extending through the wall of the housing into the block. An opening 128 which contains a threaded plug 130 is provided in the side wall of the housing for filling chamber 120 with a suitable hydraulic fluid, such as, for example, D. C. Silicone Fluid, for use by the fluid drive assembly in transmitting the rotative force from rotor 40 to impeller 50.

Mounted on the end of shaft 52 and rotatable therewith is a cam 140 which operates microswitch 26 through a cam follower member 144 pivoted to a bracket 146 on the switch casing, and a stem 148 connected to one of the switch elements 149 (Figure 14), the circuit being closed when element 149 contacts element 149'. The microswitch 26 is rigidly secured to block 58 by one or more screws. For the purpose of the present description the particular microswitch shown may be considered

as any one of a number of well known microswitches readily available on the market. These switches have a snap action and will open and close with relatively small movement on the part of the actuating member. In the particular embodiment shown in the drawings, the switch is closed by movement of stem 148 inwardly toward the switch and thus, as seen in Figures 2 and 10, the cam being in its position farthest from the switch, is in its switch open position, while, as seen in Figure 11, the cam being in its position closest to the switch, is in its switch closed position. The cam is urged to its switch open position of Figures 2 and 10 by a spring 150 connected at one end to a rod 152 joined to and movable with cam 140 and at the other to a stationary post 154 mounted on and secured to block 58. Post 154 and a second stationary post 156 mounted on and secured to block 58 form stops for rod 152 to limit the rotative movement of cam 140.

Cover 22 is sealed in fluid tight relation with the housing by an O-ring 160 and is held securely thereon by one or more screws 162 extending through the cover and the wall of the housing into block 58.

The rate of speed at which the microswitch will be closed can be changed to meet requirements by varying the strength of or tension on spring 150. This can be done by merely selecting a spring of the desired calibration and substituting it for the one in the mechanism, or an adjustable anchor member of a well known construction can be used in place of the stationary post 154. A coil spring may be used in place of the type shown in the drawings and the anchor point for one end of the coil spring can be made adjustable. The rate of speed at which the switch will close can also be changed by varying the amount of viscosity of the hydraulic fluid in chamber 120. However, in order to obtain consistent operation of our switch mechanism, it is important to select one of a number of hydraulic fluids which have a substantially constant viscosity over extreme ranges of temperatures.

In the operation of our switch mechanism mounted on an engine or other machine or apparatus, shaft 42 and rotor 40 are rotated in accordance with the speed of the rotating member being sensed, impelling the fluid in chamber 120 through holes 64 in the rotor and holes 98 in the impeller and then outwardly between blades 62 into vanes 96 of the impeller. As long as the speed being sensed is below a preselected rate as determined by the strength of or tension on spring 150, impeller 50 remains stationary and cam 140 and rod 152 remain in the position shown in Figures 2 and 10. As soon as the speed of the rotor increases sufficiently to cause the impeller to overcome the force of spring 150, cam 140 rotates in a clockwise direction as viewed in Figures 2, 10 and 11 to the position shown in Figure 11. With the cam in this position stem 148 of the microswitch is depressed to its closed switch position and contacts 149 and 149' are pressed together and are held closed as long as the speed of the rotor is sufficient to rotate the impeller and hold rod 152 against post 154. When the speed of the rotor decreases to a point below the predetermined

speed setting, spring 150 rotates cam 140 in the counter clockwise direction moving rod 152 from post 154 to post 156, and permitting the microswitch to open, breaking the circuit controlled thereby.

A few modifications in our speed responsive switch have been suggested hereinbefore. Further changes and modifications may be made without departing from the scope of the present invention.

We claim:

- 10 1. A speed responsive switch mechanism, comprising a housing having a sealed fluid chamber, a disc shaped rotor in said chamber having blades thereon and a plurality of holes spaced from the center thereof, a shaft connected to said rotor and extending through one of the walls of said chamber for driving said rotor, a cup shaped impeller in said chamber having holes in the periphery thereof and vanes thereon, fluid propelled by said rotor, said blades and vanes being disposed on facing surfaces of the rotor and impeller, respectively, a shaft connected to said impeller extending through the opposite wall of said chamber and being adapted to be driven by said impeller, a cam operatively connected to and driven by said last mentioned shaft, a pin seated in said cam and projecting radially outwardly, two spaced pins forming stops for said first mentioned pin for limiting the rotation of movement of said cam, a spring connected to said first mentioned pin for resisting the rotation of said cam, electrical contact elements outside of said chamber, and a means for operatively connecting one of said elements with said cam, whereby said contact elements are closed by the rotation of said cam.
- 20 2. A speed responsive switch mechanism, comprising a housing having a sealed fluid chamber, a disc shaped rotor in said chamber having blades thereon and a plurality of holes spaced from the center thereof, a shaft connected to said rotor and extending through one of the walls of said chamber for driving said rotor, a cup shaped impeller in said chamber having holes in the periphery thereof and vanes thereon, fluid propelled by said rotor, a shaft connected to said impeller extending through the opposite wall of said chamber and being adapted to be driven by said impeller, a cam operatively connected to and driven by said last mentioned shaft, a pin seated in said cam and projecting radially outwardly, two spaced pins forming stops for said first mentioned pin for limiting the rotation of movement of said cam, a spring connected to said first mentioned pin for resisting the rotation of said cam, electrical contact elements outside of said chamber, and a means for operatively connecting one of said elements with said cam, whereby said contact elements are closed by the rotation of said cam.
- 30 3. A speed responsive switch mechanism, comprising a housing having a sealed fluid chamber, a disc shaped rotor in said chamber having blades thereon and a plurality of holes spaced from the center thereof, a shaft connected to said rotor and extending through one of the walls of said chamber for driving said rotor, a cup shaped impeller in said chamber having holes in the periphery thereof and vanes thereon, fluid propelled by said rotor, a shaft connected to said impeller extending through the opposite wall of said chamber and being adapted to be driven by said impeller, a cam operatively connected to and driven by said last mentioned shaft, a pin seated in said cam and projecting radially outwardly, two spaced pins forming stops for said first mentioned pin for limiting the rotation of movement of said cam, a spring connected to said first mentioned pin for resisting the rotation of said cam, electrical contact elements outside of said chamber, and a means for operatively connecting one of said elements with said cam, whereby said contact elements are closed by the rotation of said cam.
- 40 4. A speed responsive switch mechanism, comprising a housing having a sealed fluid chamber, a disc shaped rotor in said chamber having blades thereon and a plurality of holes spaced from the center thereof, a shaft connected to said rotor and extending through one of the walls of said chamber for driving said rotor, a cup shaped impeller in said chamber having holes in the periphery thereof and vanes thereon, fluid propelled by said rotor, a shaft connected to said impeller extending through the opposite wall of said chamber and being adapted to be driven by said impeller, a cam operatively connected to and driven by said last mentioned shaft, a pin seated in said cam and projecting radially outwardly, two spaced pins forming stops for said first mentioned pin for limiting the rotation of movement of said cam, a spring connected to said first mentioned pin for resisting the rotation of said cam, electrical contact elements outside of said chamber, and a means for operatively connecting one of said elements with said cam, whereby said contact elements are closed by the rotation of said cam.
- 50 5. A speed responsive switch mechanism, comprising a housing having a sealed fluid chamber, a disc shaped rotor in said chamber having blades thereon and a plurality of holes spaced from the center thereof, a shaft connected to said rotor and extending through one of the walls of said chamber for driving said rotor, a cup shaped impeller in said chamber having holes in the periphery thereof and vanes thereon, fluid propelled by said rotor, a shaft connected to said impeller extending through the opposite wall of said chamber and being adapted to be driven by said impeller, a cam operatively connected to and driven by said last mentioned shaft, a pin seated in said cam and projecting radially outwardly, two spaced pins forming stops for said first mentioned pin for limiting the rotation of movement of said cam, a spring connected to said first mentioned pin for resisting the rotation of said cam, electrical contact elements outside of said chamber, and a means for operatively connecting one of said elements with said cam, whereby said contact elements are closed by the rotation of said cam.
